AUTOMATIC LUBRICANT OVERBALANCE
FOR TABLE ROLLSEarl E. Berry, Beloit, Wis., assignor to Beloit Iron
Works, Beloit, Wis., a corporation of Wisconsin

Application September 21, 1936, Serial No. 101,707

12 Claims.

(Cl. 92—44)

This invention relates to mechanism for hydraulically controlling the floating or overbalancing of paper machine forming wire supporting rollers in their bearing supports which extend under the wire. The mechanism of this invention automatically compensates for variations in pressure above the wire and for variations in vacuum or pressure beneath the wire and will maintain the rollers floating or overbalanced in their bearing supports at a pre-set degree by supplying more or less hydraulic pressure between the rollers and their bearing supports immediately upon changes in pressure above the wire or changes in pressure or vacuum below the wire.

15 In my copending application entitled "Pressure and vacuum forming paper making machine", Serial No. 71,109, filed March 27, 1936, there is described and illustrated a paper making machine in which a forming wire is supported on 20 loosely journaled table rolls extending transversely across the top of a drain box. Paper stock is fed from a pond to the traveling wire over the table rolls, and white water from the stock drains into compartments formed in the drain box. These compartments can be separately evacuated to a desired degree or a pressure can be allowed to build up in some of the compartments by retaining a head white water 25 therein. Since the rollers support the wire, the pond of stock on the wire, and the fibrous web formed on the wire, they are naturally pressed down in their bearing supports or journals. This downward pressure is increased or decreased by the amount of vacuum or pressure maintained in 30 the drain box compartments. However, a lubricating fluid, such as water, can be maintained at a fixed hydraulic pressure between the bearing supports and the rollers to overbalance the rollers and cause them to float in their bearing supports.

40 The floating of the rollers in their bearing supports causes the same to contact the top edges of the supports. These edges, therefore, act as doctors to scrape the rollers clean and prevent 45 clogging of the bearing supports with fibers from the white water which might be picked up by the rollers. In some instances the lubricating fluid can be maintained under a sufficient hydraulic pressure to flow out of the tops of the bearing supports. This outward flow of water further 50 cleans and washes the rollers.

It is obvious that the pressures above the forming wire and the pressures or vacuum in the drain box compartments will vary during the 55 operation of the machine, so that varying hy-

draulic pressures will be required to float or overbalance the rollers in their supports at the desired degree.

This invention now provides mechanism for automatically varying the hydraulic pressure of the lubricating fluid between the bearing supports and table rollers to compensate for variations in pressure over the forming wire and pressures or vacuum under the forming wire.

In accordance with this invention, water or other lubricating fluid is supplied to a conduit or pipe line under pressures higher than the pressure needed for floating the table rollers in their bearing supports. A pressure reducing valve is included in this supply conduit and is set to maintain the low side of the valve under a fixed pressure. A pipe line or conduit communicates with the low side of the valve and with each of the bearing supports for the table rolls whereby water is supplied to the table rolls under a fixed hydraulic pressure. As this pressure decreases because of loss of water from between these bearing supports and table rolls, the pressure reducing valve automatically compensates for this reduced pressure by allowing the flow of more water into the bearing supports.

Therefore, as long as the pressures on the forming wire and the pressures or vacuum under the forming wire remain constant, the usual type of pressure reducing valve will serve to maintain 30 a constant hydraulic pressure between the bearing supports and their table rolls for overbalancing or floating the rolls. However, when the pressure above the wire and the pressures or vacuum below the wire vary so as to increase or decrease the load on the table rolls, the usual pressure reducing valve cannot compensate for these 35 variations, because the pressure on the low side of the valve will not be changed.

According to this invention, therefore, "Sylphon" bellows operated by pressures above and below the wire, such as, for example, pressures at the bottom of a pond of stock above the wire and pressures or vacuum in the compartments of the drain box, are operatively connected to the 45 pressure reducing valve through a lever and link arrangement so as to increase or decrease the pressure on the low side of the valve to compensate for the increased or decreased pressure on the table rolls.

It should be understood that diaphragms, pressure bulbs, or other means capable of transforming variations in pressure into mechanical movements are operable in place of "Sylphon" bellows.

It is then an object of this invention to provide 55

mechanism for controlling the floating or overbalancing of table rolls in bearing supports.

A further object of this invention is to provide an automatic mechanism to compensate for variations in pressures above the forming wire of a paper machine and variations in pressures or vacuum below the forming wire of the paper machine to maintain table rolls floating in their bearing supports.

10 A specific object of this invention is to hydraulically overbalance table rolls in their bearing supports irrespective of variations in load carried by the rollers without wasting hydraulic fluid.

15 A further object of this invention is to hydraulically overbalance each set of table rolls loosely journaled in bearing supports above a plurality of compartments in a white water receiving drain box mounted under the forming wire of a paper machine and to vary the hydraulic pressure under the table rolls with variations 20 in the load carried by the rolls.

25 Other and further objects of this invention will become apparent to those skilled in the art from the following detailed description of the annexed sheet of drawings which discloses a preferred embodiment of the invention.

On the drawing:

30 Figure 1 is a diagrammatic side elevational view, with parts shown in vertical cross section, 35 of the automatic lubricant overbalance for table rollers in accordance with this invention.

As shown on the drawing:

35 The reference numeral 10 designates the forming wire of a paper machine of the Fourdrinier type adapted to travel over a drain box 11 while supported on a plurality of small diameter table rolls 12 which are loosely journaled in bearing supports 13 extending transversely across the top of the box 11 on the end walls of the box, 40 such as 14, transverse bars 15 carried by the box, and partition walls 16 formed in the box. The bearing supports 13 extend transversely across the top of the box 11 for substantially the entire length of the rollers 12 and extend for more than 45 180° around the peripheries of the rollers.

50 The end walls 14 of the drain box 11, the transverse bars 15 in the drain box 11, and the partition walls 16 of the drain box 11 each have longitudinal wells or passageways 17 extending 55 across the tops thereof in communication with the inside bearing surfaces of the bearing supports 13 through openings 18 formed in the bottoms of the bearing supports.

55 The partition walls 16 of the drain box 11 define a plurality of compartments such as 19 and 20 in the drain box. The bottom of the drain box 11 is closed by a sloping bottom pan 21. The partition walls 16 do not extend to the bottom of the pan 21 but terminate in spaced relation 60 therefrom. The ends of the partition walls 16 are slotted as at 22. Slides 23 are vertically slidable in the slots 22 of the partition walls 16 by means of lift screws (not shown) which may extend 65 through the bottom pan 21. The compartments 19 and 20 receive white water drained through the forming wire 10, and drainage of this white water from the compartments 19 and 20 can be regulated by positioning the slides 23.

70 A head box 25, of the type more fully described in my above referred to copending application, Serial No. 71,109, is mounted above the forming wire 10 and has an open bottom portion in communication with the forming wire. A slice plate 75 26 is mounted at the front end of the head box

25, preferably at the end of the compartment 19 in the drain box 11. A nozzle 27 supplies a stream of stock 28 to the head box 25. The lower lip 29 of the nozzle 27 fits snugly over the wire 10, while the upper lip 30 of the nozzle 27 is in spaced relation above the wire 10. The stock 28 flowing through the nozzle 27 is thus directed onto the forming wire 10 in a confined area behind the slice plate 26 and ahead of the end of the lower lip 29 of the nozzle. This stock depositing area is preferably above the compartment 19 of the drain box. Excess stock from the nozzle 27 flows around the end of the upper lip 30 of the nozzle to form a pond 31 behind the slice plate 26. An overflow discharge outlet 32 can be provided in the head box 25 for removing an excessive amount of stock from the pond 31 if desired.

20 The white water from the stock on the wire 10 is drained into the compartment 19 under controlled conditions. For example, the compartment 19 can be evacuated or a head of white water can be allowed to build up in the compartment for maintaining a pressure in this compartment. As the wire advances over the compartment 19 beyond the slice 26, it is subject to conditions prevailing in the compartment 20 of the drain box 11. This compartment 20 can be maintained under a higher or lower degree of 25 vacuum than the compartment 19 if desired, and as a result the formation of a web W on the wire 30 10 can take place either before the wire advances under the slice 26 or after the wire advances under the slice. The web W has additional water extracted therefrom by suction maintained in the compartment 20 or succeeding compartments 35 in the drain box.

It is evident that the head of stock in the pond 31 will vary somewhat during the operation of the machine, as well as the degree of 40 vacuum or the pressure maintained in the compartment 19 of the drain box 11. Since those table rolls 12 mounted above the compartment 19 and the walls defining this compartment must carry their own weight, the weight of the 45 wire, and the pond of stock 31 above the wire, it follows that they deflect downwardly in their bearing supports 13.

50 In order to provide a free rotation of the rollers in their bearing supports, it is desirable to 55 overbalance or float these rollers by hydraulic pressure. For this purpose the passageways 17 formed in the bars 15 within the compartment 19, in the partition walls 16 defining the compartment 19 and in the end wall 14 of the drain box, are in communication through passageways 35 with a pipe line 36. The pipe line 36, in turn, communicates through a pressure reducing valve 37 with a water supply line 38. Water is thus supplied from a high pressure supply line 38 60 through a pressure reducing valve 37 into a low pressure supply line 36 and from that into the passageways 17 from which it can flow through the openings 18 in the bearing supports into contact with the rollers 12 to overbalance or float 65 these rollers in their bearing supports.

For a given load on the roller 12, the pressure reducing valve 37 can be set to maintain a fixed pressure in the pipe line 36 sufficient to overbalance or float the rollers. However, when the 70 load on the rollers is changed by variations in pressure above the forming wire or by variations 75 in pressure or vacuum in the compartment 19 of the drain box 11, hydraulic pressure in the pipe line 36 will not be increased or decreased in

order to maintain the same floating of the rolls. These variations can be compensated for, according to this invention, by providing a control device for the pressure reducing valve 37 to change the pressure in the line 36 in accordance with the variations in pressure above or below the forming wire. For this purpose, a pair of superimposed "Sylphon" bellows 40 and 41 are mounted on opposite sides of a supporting plate 42 which is suspended from a panel such as 43 by means of brackets 44. The interior of the bellows 40 communicates through a pressure tube 45 with the bottom of the pond of stock maintained above the forming wire 10 as at 46. The interior of the bellows 41 communicates through a pressure tube 47 with the interior of the compartment 19 in the drain box 11.

A lever 48 is pivoted to the top of the bellows 40 as at 49 and to the panel 43 as at 50. A link 51 connects the lever 48 with a second lever 52 pivoted to the bottom of the bellows 41 as at 53 and to the panel 43 at 54. The link 51 is pivoted to the levers 48 and 52 at 55 and 56 respectively.

A tension spring 57 is secured on the lever 48 between the pivot points 49 and 50 thereof. The other end of the tension spring 57 is secured to an adjusting screw 58 which extends through the bellows supporting plate 42 and has a thumb nut 59 threaded therearound in abutment with the underside of the plate. In this manner the tension on the spring 57 can be set to hold the bellows 40 and 41 through their link and lever connections in neutral position, as when the pressure reducing valve 37 is maintaining the exact amount of hydraulic pressure in the bearing supports to float the rollers. However, assuming that the pond of stock 31 builds up above the wire 10 thereby increasing the pressure on the wire. The increased head of stock in the pond 40 will force stock through the pressure tube 45 into the bellows and expand the bellows against the spring tension. The expansion of the bellows raises the pivot point 49 of the lever 48 and tilts the lever about its pivot point 50. The pressure reducing valve 37 is joined through a rod 60 to the lever 48 between the pivot points 49 and 50, so that when the bellows 40 expands, the rod 60 will raise to move an actuating arm 61 of the valve upwardly for further opening the valve and causing an increased pressure in the line 36. However, since the increased head of stock in the compartment 19 is transmitted into the bellows 41 to expand the bellows thereby lowering the pivot point 53 of the lever 52 to tilt the lever about its pivot point 54 to raise the end 56 thereof. The link 51 in turn tends to force the end of the lever 48 upwardly thereby tending to offset the amount of raising of the rod 60 by the lever 48. If, on the other hand, the vacuum in the drain box increases with the increase of the head of stock on the wire, the bellows 41 will be collapsed, the end of the lever 52 thrown downward to move the link 51 downward and further raising the rod 60 to increase the opening of the pressure reducing valve 37.

It is thus evident that the variable load carried by the rollers is determined by the pressure or vacuum within the compartment 19 of the drain box, and the head of stock maintained above the

wire 10. An increase in pressure in the compartment 19 will tend to close the pressure reducing valve 37, while an increase in vacuum in the compartment 19 will tend to open the valve. At the same time, an increase in pressure on the wire 10 by the pond 31 will tend to open the valve 37, while a decrease will tend to close the valve and any simultaneous opposed variations in the compartment 19 and on the wire 10 will be compensated for through the lever and linkage 10 arrangement.

Since the table rolls 12 are definitely spaced between their centers, each table roll carries a definite proportion of the load so that the pressure reducing valve can be set to maintain a sufficient hydraulic pressure beneath the rolls for a desired amount of overbalance of these rolls. The valve, however, cannot be set to compensate for variations in pressures on top or underneath the wire as encountered during operation of the machine, and for this reason the bellows and lever arrangement are necessary to effect this compensation. Thus, from the pressure readings on pressure gauges 65 and 66 communicating with the bottom of the pond of stock and with the interior of the compartment 19 of the drain box respectively, it can be determined how much pressure will be needed in the line 36 to maintain a sufficient hydraulic pressure for overbalancing the rolls to a desired degree. A pressure gauge 67 can be inserted in the line 36 and the spring 57 can be set beforehand to regulate the valve 37 so that this pressure will be maintained in the line 36. Then, when the vacuum or pressure in the compartment 19 changes or when the head of stock maintained above the wire changes, the bellows will be expanded or contracted responsive to these changes to move the lever arrangement against the spring pressure for opening or closing the valve 37.

The compartment 20 of the drain box 14 is illustrated as being maintained outside of the pond area 31 ahead of the slice 26. Since the pressure above the rollers 12 in this compartment 20 will thus be constant, it is not necessary to include the top bellows or pressure tube described above, and the hydraulic pressure regulating mechanism is thus simplified.

As shown in the right hand end of Figure 1, the passageways 17 in the transverse bars 15 in the compartment 20 and in the partition wall 16 of the compartment 20 communicate through conduits 70 with a water pipe 71. The water pipe 71 communicates through a pressure reducing valve 72 with a high pressure water supply line 73.

A "Sylphon" bellows 74 is mounted on a plate 75 suspended by brackets 76 from a panel 77. The interior of the bellows 74 is in communication through a pressure tube 78 with the interior of the compartment 20. The top of the "Sylphon" bellows is pivoted to a lever 79 at 80. The lever 79, in turn, is pivoted to the panel 77 at 81, and is joined at its end with a rod 82 pivoted to an actuating arm 83 of the pressure reducing valve 72.

A tension spring 84 is secured at one end to the lever 79 between the pivots 80 and 81 thereof. The other end of the spring 84 is secured to a threaded rod 86 extending through a bracket 87 fastened on the panel 77. A thumb nut 88 is threaded around the rod 86 and abuts the bracket 87.

The amount of vacuum in the compartment 20 of the drain box can be ascertained by a read-

ing of the vacuum gauge 89 in the pressure tube 78. Likewise, the amount of pressure in the low side of the pressure reducing valve 72 can be ascertained by a reading of the pressure gauge 90 in the line 71 supplying water to overbalance the table rolls 12 in the compartment 20. From the vacuum reading on the gauge 89, it is possible to ascertain the normal degree of vacuum maintained in the compartment 20 and to set the tension of the spring 84 so as to maintain the pressure reducing valve 72 closed against the spring pressure a desired amount for supplying just enough hydraulic pressure to the line 71 for overbalancing the rolls. However, when the vacuum increases in the compartment 20, the bellows 74 will be collapsed to move the lever arm 79 downward against the spring pressure and to raise the end of the lever upward thereby raising the rod upward for further opening the pressure reducing valve 72 to increase the hydraulic pressure and maintain the rolls overbalanced. It is obvious that an increase of vacuum in the compartment 20 will increase the pressure on the rolls. On the other hand, when the vacuum in the compartment 20 falls, the bellows 74 will be expanded to allow the spring 84 to further close the pressure reducing valve 72 thereby decreasing the hydraulic pressure around the table rolls and maintaining the same overbalanced with less pressure.

From the above description, it should be understood that this invention provides for the floating or overbalancing of table rolls in journal supports and the maintenance of a desired degree of overbalance irrespective of variations in pressure conditions above and below the forming wire which the rollers support.

I am aware that many changes may be made and numerous details of construction may be varied through a wide range without departing from the principles of this invention, and I, therefore, do not purpose limiting the patent granted hereon otherwise than necessitated by the prior art.

I claim as my invention:

1. Automatic lubricant overbalance for paper machine table rollers which are loosely mounted in bearing supports along their lengths under the forming wire of a paper machine comprising a liquid conduit for supplying a liquid between the rollers and their bearing supports, a pressure reducing valve in said conduit, means for setting said valve to provide a constant hydraulic pressure of liquid in the bearing supports, and means responsive to changes in load on the rollers for actuating said valve to increase or decrease the hydraulic pressure in the bearing supports when the load on the rollers is increased or decreased, thereby maintaining the rollers hydraulically overbalanced in their bearing supports to a predetermined degree.

2. Automatic lubricant overbalance for paper machine table rollers which are loosely journaled in bearing supports along their lengths below the forming wire of a paper machine comprising a liquid conduit for supplying a liquid lubricant between the rollers and their bearing supports, a pressure reducing valve in said conduit, means for setting said valve to provide a constant hydraulic pressure in the bearing supports, pressure responsive bellows communicating with the bottom of a pond of stock fed to the forming wire of the machine, and a lever arm in pivotal connection with said pressure reducing valve for transmitting expansion and collapsing movement of the bellows to the valve for opening or closing

the same to increase or decrease the hydraulic pressure in the bearing supports when the pressure at the bottom of the pond of stock on the wire increases or decreases.

3. In a paper making machine, in combination, a forming wire, a drain box mounted under said forming wire, bearing supports carried by said drain box transversely across the top thereof, table rollers loosely journaled in said bearing supports, a stock vat over said wire for maintaining a pond of stock thereon, a liquid conduit for supplying liquid between the table rollers and their bearing supports, a pressure reducing valve in said conduit, means for setting said valve to maintain a constant pressure of liquid in the bearing supports, pressure expansible and contractable devices in communication with the bottom of a pond of stock on the wire and the interior of the drain box respectively, lever arms pivotally connected to said devices and to a supporting member, a link arm connecting the ends of the levers, and means connecting an actuating member of said pressure reducing valve to one of said lever arms between its pivot points whereby variations in pressure at the bottom of the pond of stock on the wire or variations in pressure or suction in the drain box will collapse or expand the devices to move the levers for controlling the operation of the pressure reducing valve to increase or decrease the liquid pressure in the bearing supports in compensation for the increased or decreased pressure above and below the table rollers.

4. A paper making machine comprising in combination a forming wire, a drain box below said wire, bearing shells extending transversely across the top of the drain box in spaced parallel relation to each other, table rolls in said shells for supporting the forming wire, a stock vat for a pond of stock above the wire, a pair of oppositely disposed bellows adjacent the drain box secured at one end thereof on a fixed member, levers pivoted to the free ends of the bellows and to fixed points intermediate their ends, a link joining the ends of the levers, tubes joining the interiors of the bellows with the bottom of the pond of stock in the drain box respectively, a fluid pressure line for supplying lubricants to the bearing shells, a pressure reducing valve in said line having a control member thereof pivoted to one of said levers whereby movement of the levers by the bellows opens or closes the valve to increase or decrease the pressure in the supply line, and movement of the bellows is controlled by variations in pressure in the pond of stock above the wire and variations in pressure or vacuum in the drain box.

5. A device for maintaining table rollers overbalanced to a predetermined degree in their bearing supports which comprises a fluid pressure line for supplying lubricants under pressure to the bearing supports of the table rollers, a pressure reducing valve in said supply line, a bellows fixedly secured at one end, a lever pivoted to the free end of the bellows and to a fixed point intermediate the ends of the lever, a rod connecting an actuating member for the pressure reducing valve with the end of the lever, and means for actuating said bellows from variations in load on the table rolls to raise or lower the lever thereby opening or closing the pressure reducing valve to increase or decrease the pressure in the supply line.

6. In a paper making machine, in combination, a forming wire, a plurality of small diameter table

5 rolls supporting said forming wire, bearing supports loosely journaling the table rolls throughout substantially their entire length, a conduit for conveying liquid under pressure to the bearing supports for delivery around the rolls, a valve in said conduit for controlling the pressure of said liquid in the bearing supports, and automatic control means for said valve operated by variations in loads on the rolls for progressively opening 10 or closing the valve as the loads on the rolls increase or decrease.

15 7. The method of balancing table rolls in their bearing supports which comprises surrounding the under side of each table roll with an open topped bearing shell extending more than 180° around the roll, said shells having interior diameters larger than the external diameters of the rolls to loosely journal the rolls therein, flowing 20 a liquid into the shells under sufficient atmospheric pressure to raise the rolls off of the bottoms of the shells and automatically varying the superatmospheric pressure of the liquid being supplied to the shells in accordance with variations in the load carried by the rolls to maintain 25 a constant balanced condition of the rolls in their shells.

30 8. The method of balancing table rolls in their bearing supports which comprises surrounding the under side of each table roll throughout its length with an open topped bearing shell extending more than 180° around the rolls, said shells having interior diameters larger than the external diameters of the rolls to loosely journal the rolls therein, flowing a liquid under superatmospheric pressure into the bottoms of the bearing supports against the table rolls to relieve 35 the pressures between the rolls and the bottoms of the shells to any desired amount and automatically varying the superatmospheric pressure of the liquid being supplied to the bearing supports in accordance with variations in the load carried by the rolls to maintain said relief of pressure between the rolls and the bottoms of the shells constant.

40 9. In a paper making machine, in combination, a forming wire, a plurality of small diameter table rolls supporting said wire, bearing supports loosely journaling the table rolls throughout substantially their entire length, means for supplying a fluid under superatmospheric pressure between the bearing supports and the table rolls, and separate means actuated 45 by variations in load carried by the table rolls for

varying the superatmospheric pressure of the fluid being supplied to the rolls.

10 10. In a paper making machine, in combination, a forming wire, a plurality of small diameter table rolls supporting said forming wire, bearing shells loosely journaling the table rolls throughout their entire length and extending around the rolls for more than 180 degrees of their peripheries, means for supplying a lubricating liquid under superatmospheric pressure into the bottoms of the bearing shells for acting against the table rolls to relieve the pressures between the rolls and the bottoms of the shells to any desired amount, and separate means actuated by variations in load carried by the rolls for varying the superatmospheric pressure of the liquid being supplied to the bearing shells for maintaining said relief of pressure between the rolls and the bottoms of the shells constant.

15 11. In a paper making machine, in combination, a forming wire, a plurality of elongated small diameter table rolls supporting the wire, bearing shells disposed under the table rolls and for more than 180 degrees around the peripheries thereof throughout substantially the entire length 20 of the rolls, said bearing shells having a larger internal diameter than the external diameter of the rolls to loosely journal the rolls, means for supplying a liquid under superatmospheric pressure between the bearing shells and the table rolls, 25 means for maintaining a pond of stock above the forming wire, and separate means actuated by variations in the weight of said pond of stock on the wire for varying the superatmospheric pressure of the fluid being supplied to the bearing 30 shells.

35 12. In a paper making machine, a drain box, a plurality of bearing shells carried by the drain box at the top thereof, table rolls having an exterior diameter less than the interior diameter 40 of the bearing shells rotatably mounted in the bearing shells in loose engagement therewith, means for supplying water under superatmospheric pressure between the table rolls and bearing shells for overbalancing the rolls in the shells, 45 means for evacuating the drain box, and separate means actuated by variations in load carried by the table rolls for varying the superatmospheric pressure of the fluid being supplied to the rolls to maintain a constant balanced condition of the 50 rolls in their shells.

EARL E. BERRY.
